UNITED STATES PATENT OFFICE.

JOHN A. PERKINS, OF MINNEAPOLIS, MINNESOTA.

GRAIN SEPARATOR.

Application filed December 3, 1923, Serial No. 678,312. Renewed December 24, 1925.

This invention relates to improvements in separators particularly adapted for use in separating from each other, materials of different sizes, and more particularly relates to such separators adapted to separate wheat from weed seeds, wild oats and other foreign materials.

Grain separators such as are commonly used at the present time, usually employ a series of shaking sieves, arranged one above another in spaced relation, through which the grain is passed for separation. Machines of this type usually have a fan or blower mounted at one end thereof adapted to direct a flow of air through the machine to carry off the lighter materials. These machines have a very limited capacity, and are therefore usually hand operated, their construction being such that it would be impractical to increase their size and capacity sufficiently to warrant operating them by power. It is also necessary in most cases to pass the material through the machine several times before a good separation can be made.

Other types of machines employ a series of disks mounted upon a horizontal shaft within a suitable casing. These disks usually have their opposed surfaces covered with indentations or pockets of such size and shape as to pick out the different size materials as the disks revolve through the grain.

The novel separator featured in this invention embodies a different principle of separation from that employed by machines in use at the present time. As here shown, and described, the separating means consists of an endless steel belt arranged at an incline within the casing of the machine and extending from end to end thereof. The outer exposed surface of this belt is covered with suitable indentations or pockets of different sizes, preferably arranged in groups extending longitudinally of the belt, the groups being arranged progressively across the belt, so that the grain first passes over the smaller pockets whereby the finer seeds are taken out, and so on progressively for the several sizes of pockets. The grain is delivered onto the belt from a suitable grain feeding mechanism located at one end of the machine, and is distributed over the surface thereof by a suitable distributing means. The material or grain thus deposited upon the surface of the belt is supported entirely thereby, and as the belt travels upwardly and outwardly from beneath the grain, the

smaller pockets or indentations, provided in one section of the belt surface, will pick up the finer particles and materials such as small seeds, dirt, etc., while the relatively larger pockets provided in another section of the belt will pick up the wheat. During the operation of thus separating the small seeds and wheat from the coarser and larger materials, such as oats which are discharged from the end of the machine, the movement of the belt will cause the grain, deposited thereon, to be thoroughly agitated and will impart thereto, a rolling action. Such action will cause all of the material or grain to come in contact with the surface of the belt, resulting in a thorough and complete separation being obtained by passing the grain through the machine once only. It is to be understood that the belt is positioned at such an angle as to convey only material deposited in the pockets provided in the surface thereof, the coarser material rolling by gravity back to the lower portion of the belt and across the surface thereof.

The particular object of this invention, therefore, is to provide an improved grain separator of simple and inexpensive construction and of large capacity.

Other objects of the invention will more fully appear from the following description and the accompanying drawings and will be pointed out in the annexed claims.

In the drawings, there has been disclosed a structure designed to carry out the various objects of the invention, but it is to be understood that the invention is not confined to the exact features shown, as various changes may be made within the scope of the claims which follow.

In the accompanying drawings, forming part of this specification,

Figure 1 is a view in end elevation of my improved machine, showing the means provided thereon for taking up slack in the steel belt;

Figure 2 is a transverse sectional view on the line 2—2 of Figure 3, showing the endless steel belt and its relative position with reference to the hopper and the grain feeding mechanism;

Figure 3 is a longitudinal sectional view on the line 3—3 of Figure 2, showing how the grain is fed into the machine at one end thereof, and also showing the means provided for distributing the grain over the full width of the belt and for discharging

the oats and coarser material from the end of the machine;

Figure 4 is a detail sectional view on the line 4—4 of Figure 2, showing the spiral conveyor provided at the rear of the machine for discharging the separated materials from the machine;

Figure 5 is an enlarged detail sectional view on the line 5—5 of Figure 3, showing 10 how the grain is delivered onto the inclined surface of the steel belt and also showing the rolling action of the grain when the machine is in operation;

Figure 6 is a detail sectional view on the 15 line 6—6 of Figure 3, to show the fluted feed roll;

Figure 7 is an enlarged detail view of a portion of one of the steel sections of the belt, showing the different size indentations 20 provided thereon;

Figure 8 is a cross sectional view on the line 8—8 of Figure 7, showing the preferred form of indentations provided for separating the wheat from the other materials;

25 Figure 9 is a similar view on the line 9—9 of Figure 7, showing the smaller indentations provided for separating the weed seeds and finer materials from the wheat;

Figure 10 is a similar view, showing a 30 modified form of belt;

Figure 10^A shows another modified form of belt construction;

Figure 11 is another modification showing a belt having its surface provided with 35 indentations of various sizes;

Figure 12 is a view in front elevation of a modified form of separator, partially broken away to show the interior thereof; and

40 Figure 13 is an end view of Figure 12.

In the selected embodiment of the invention here shown, there is illustrated a grain separator having a casing or frame, preferably of metal, comprising a front wall 14, 45 rear wall 15, end walls 16, top wall 17 and preferably a bottom wall 18.

An endless belt or apron, composed preferably of a plurality of steel sections 19, suitably hinged together as shown in Figure 50 2, is arranged at a suitable angle within the casing and preferably extends from end to end thereof. The outer exposed surface of this belt is preferably closely covered with suitable indentations or pockets of different 55 sizes, adapted to pick up different size materials and convey them to the back of the machine. The surface of the belt, adjacent the feeding end of the machine, is preferably provided with small indentations or 60 pockets 20, as shown in Figures 3, 7 and 9, of such size and shape as to pick up only small materials, such as weed seeds, wild peas, particles of dirt, etc., when deposited thereon, as shown in Figures 2 and 5. These 65 small pockets preferably cover approximate-

ly one-third of the width of the belt's surface. The remainder of the belt's surface is preferably covered with larger pockets 21, as shown in Figures 3, 7 and 8, of such size and shape as to receive kernels of wheat, 70 and thereby convey them to the back of the machine. the larger materials such as wild oats, barley, small sticks etc., being too large to be received therein. It is to be understood that the angle or incline of the belt is such that no material can be elevated to the back of the machine unless deposited in the pockets 20 and 21, provided in the surface thereof. It may be found desirable in the practical use of this machine, to provide 75 more than two sizes of pockets in the surface of the belt, as shown in Figures 11 and 12. As here shown, the surface of the belt is covered with three sizes of indentations, the portion of the belt adjacent the discharge end of the machine preferably being covered with larger indentations 22. Referring to Figure 8, it will be noted that the larger pockets are preferably slightly undercut on the lower side, thereby forming in effect a bucket into which the kernels of wheat may drop and thus be elevated to the rear of the machine. By thus forming the pockets, the capacity of the machine will be greatly increased, as more than one kernel may be 80 carried in each pocket, and also there will be less danger of the kernels dropping out of the pockets while being elevated to the receiving means provided at the rear of the machine. 85

The upper portion of the belt is preferably supported by means of suitable pulleys 23, mounted on a horizontal shaft 24 which is rotatably mounted in suitable bearings 25 provided at each end of the machine. As shown in Figure 2, the peripheral surfaces of these pulleys are preferably covered with a flexible facing 26 for the purpose of providing a better contact with the metallic blocks 27, preferably secured to the inner 90 surfaces of the belt sections 19 in alinement with the pulleys. The flexible facing 26 also functions to eliminate noise and to provide a quiet running machine. A toothed wheel or sprocket 28 is preferably mounted on the shaft 24, adapted to cooperate with the spaced teeth 29, secured to the belt sections, for the purpose of providing a positive drive for the belt. In machines of small size and capacity it may be necessary to employ only 95 one such sprocket in which case it would preferably be located in the center of the machine, the ends of the belt being supported on the faced pulleys 23. If desired, the sprockets 28 may be eliminated, as the 100 frictional contact between the belt and the faced pulleys 23 has been found sufficient to drive the belt. In larger machines, however, it has been found desirable to employ two 105 such drive sprockets arranged one at each 110

115

120

125

130

end of the belt, the central portion of the belt being similarly supported by means of the pulleys 23.

The lower portion of the belt is supported by means of similar pulleys 31 mounted upon a shaft 32 which is rotatably mounted in bearings 33 secured to a pair of yieldingly mounted brackets 34, provided at each end of the machine. As particularly shown in Figure 1, the lower ends of the brackets 34 are pivotally connected to the end walls 16 of the machine by means of pivot bolts or studs 35. The upper end of each bracket is preferably connected to one end of a suitable tension spring 36, having its other end secured to the casing by means of a hook-bolt 37. Elongated apertures 38 are provided in the end walls of the casing to provide clearance for the yieldingly mounted shaft 32, outwardly projecting therethrough. The above described mechanism functions as a take-up means for the belt, thereby always keeping the belt taut.

The means provided for feeding or discharging the grain onto the indented surface of the belt consists preferably in the provision of a suitable hopper and feeding mechanism mounted at one end of the machine. As shown in Figures 2, 3, 5 and 6, a hopper 39 is provided in one corner of the casing, preferably adjacent the front side thereof. This hopper is preferably formed by means of a portion of the front wall 14, a portion of the end wall 16, an inner wall 41 and an end wall 42. An inclined plate 43, preferably secured to the front wall 14 of the casing is provided within the hopper and is so arranged as to provide an elongated opening 44 at one side of the hopper through which the material may pass for delivery onto the inclined surface of the belt. Means are provided for regulating the flow of grain through the opening 44. Such means consists preferably in the provision of an adjustably mounted slide 45 which functions to increase or decrease the length of the opening 44 to permit more or less grain to be delivered onto the belt, as desired. This slide is preferably supported upon a pair of rails 46, preferably of angle bar, secured to the opposed walls of the hopper, as clearly shown in Figures 2 and 6. A rod 47, having a hand grip 48, is secured to one end of the slide and preferably outwardly projects therefrom through an aperture provided in the end of the casing. By means of this rod the slide 45 may be readily and conveniently moved or adjusted to regulate and control the flow of grain through the opening 44.

Means are also provided in conjunction with the hopper here shown, whereby a uniform and constant flow of grain may be delivered onto the indented surface of the inclined belt or apron, while the machine is

in operation. This is an important feature and is necessary in order to obtain a thorough and efficient separation of the different materials. Such means consists preferably in the provision of a fluted feed roll 49, mounted upon a shaft 51 which is rotatably mounted in bearings 52 and 53 secured to the end walls of the machine. This feed roll is so arranged that the grain passing through the opening 44 is delivered onto one side thereof, and as the feed roll revolves in the direction indicated by the arrows in the drawings, the grain will be delivered onto the belt in a uniform flow. A yieldingly mounted gate 54 is suitably so hinged to the lower marginal edge of the inner wall 41 of the hopper 39, and is yieldably held in normal position, adjacent one side of the feed roll 49, as shown by full lines in Figures 2, 5 and 6, by means of a suitable spring 55. The purpose of thus yieldably mounting the gate 54 is to provide means whereby large materials such as sticks, etc., may pass between the feed roll and the gate without causing injury or damage thereto.

As particularly shown in Figure 3, the end of the slide 45, adjacent the rod 47, is preferably bent at substantially right angles, thereby forming a depending portion or plate 56, adapted to cooperate with a similar plate 57, suitably secured to the slide 45, to provide a guide or bearing for a circular disk 58 rotatably mounted therebetween and carried by the fluted feed roll 49. The depending plates 56 and 57 are provided with circular apertures of suitable size to permit the feed roll to rotate therein without interference. As shown in Figure 6, the circular disk 58 is provided with an aperture so shaped as to conform to the contour of the feed roll, thereby closing the gaps or openings between the longitudinal ribs of the feed roll and the bore of the apertures provided in the plates 56 and 57, thus preventing the grain from feeding axially along the feed roll. The longitudinal movement of the disk 58 with reference to the feed roll is controlled by the movement of the slide 45.

Means are provided for preventing the grain from sliding or falling off the inclined surface of the belt when delivered thereon. As shown in Figures 2 and 5, a longitudinal plate 59, preferably arcuately formed, is secured to the front wall 14 of the casing and downwardly and inwardly extends therefrom so that its lower terminal edge just clears the top surface of the belt, thus forming in effect a trough, into which the grain is discharged from the feed roll. A brush 61 of suitable material, is preferably secured to the front wall of the machine by brackets 62 and inwardly projects therefrom through an elongated aperture 63 provided

in the wall. This brush preferably extends from end to end of the machine and is so arranged as to have its bristles bearing against the upper inclined surface of the belt for the purpose of closing the gap between the lower edge of the plate 59 and the surface of the belt, thereby preventing grain from falling therebetween.

Means are also provided for longitudinally feeding and distributing the grain across the full width of the belt or apron. Such means preferably consists in the provision of a spiral feed screw or conveyor 64 mounted on the shaft 51 in abutting relation to the feed roll 49, and extending therefrom to the opposite end of the machine. As shown in Figure 3, this conveyor is preferably arranged at a slight angle with reference to the shafts 24 and 32, i. e., the discharge end thereof is preferably slightly higher than the receiving or feed end thereof. When the grain is delivered onto the belt at the receiving end of the machine, as shown in Figures 2 and 3, it will tend to pile up in the so-called "trough" formed by the inclined surface of the belt and the plate 59, until it contacts with the revolving feed screw 64 and is thereby distributed over the entire width of the belt. By thus arranging the conveyor 64 at an angle, the discharge end thereof will be a greater distance from the belt's surface, thereby causing it to discharge or sweep only the lighter materials from the machine. Referring to Figures 2 and 5, it will be clearly noted that as the upper inclined portion of the belt or apron travels upwardly, the grain in direct contact therewith will be carried outwardly from beneath the mass of grain resting upon the belt. All material which is too large to be received in the pockets 20 and 21, will roll by gravity back into the mass of grain, caused by the belt being positioned at such an angle as to convey only the material deposited in the pockets thereof. Thus, the mass of grain resting upon the belt's surface will be in continual motion and a rolling action will be imparted thereto, as indicated by the arrows in Figures 2 and 5, thereby causing all of the grain to come in direct contact with the surface of the belt resulting in a thorough and complete separation being made of the different materials.

As shown in Figures 2 and 4, a two-way conveyor is preferably provided at the rear of the machine, one end of which is adapted to receive the weed seeds and finer materials, while the other end thereof is adapted to receive the wheat. This conveyor preferably consists of a trough 65, extending the full length of the machine and having its ends suitably secured to the end walls 16 of the casing. A shaft 66 is positioned within the trough and is supported in bearings 67, provided at each end of the machine. A right

hand spiral 68 is concentrically mounted on the shaft 66 adjacent the head or receiving end of the machine. The length of the spiral 68 is substantially equal to the width of that portion of the belt's surface which is covered with the small indentations 20. Thus, as the weed seeds are delivered from the belt into the conveyor or trough 65, they will be conveyed to the head end of the machine and discharged therefrom into a spout 69, from whence they may be delivered to a suitable receiving means, not shown. A left hand spiral 71 is also mounted upon the shaft 66, preferably in abutting relation with the right hand spiral 68, and extends therefrom to the other end of the machine. This spiral functions to convey the wheat, which is delivered into the conveyor from the belt, to the tail end of the machine and into a similar spout 72.

A rotary brush 73 is preferably provided at the discharge end of the machine, as shown in Figures 2 and 3, and is supported by means of a shaft 74 rotatably mounted in suitable bearings 75 secured to the end walls 16. This brush is so arranged as to contact with a portion of the belt's surface, having a sweeping effect thereon, as shown by the dotted lines in Figure 2. The purpose of the brush is to prevent any large materials such as oats, barley and small sticks, which may partially drop into the pockets 21, from being elevated by the belt and delivered into the conveyor at the rear of the machine.

This separator may be operated from any suitable source of power desired. In Figures 3 and 4, I have shown the ends of the shafts 24, 51, 66 and 74 projecting outwardly from the end wall 16 of the casing, and suitable pulleys or sprockets may be mounted on these shafts and operated by means of a flexible belt 76, as indicated by the dotted line in Figure 1. The driving means, however, form no part of the present invention and are therefore not shown in detail.

In the operation of this novel separator the grain and other material is first delivered onto the inclined surface of the belt, covered with the small indentations or pockets 20, by means of the fluted feed roll 49. As the grain is thus deposited upon the belt the finer materials such as weed seeds, wild peas, particles of dirt, etc., will drop into the small pockets 20 and will be elevated to the rear of the machine and delivered into the conveyor trough 65, as shown in Figure 2, the angle of the belt being such that the larger materials, which are too large to drop into the small pockets, will roll back onto the constantly moving mass of grain supported on the lower portion of the belt beneath the feed roll and the feed screw 64. Due to the action of the belt traveling beneath it, the grain will be kept in a constant

rolling motion, as indicated by the arrows in Figures 2 and 5, thereby causing all of the grain to come in direct contact with the indented surface of the belt. As the small 5 seeds also have a natural tendency to settle to the bottom of the mass, they soon come in contact with the belt's surface and drop into the pockets 20, resulting in all of the small seeds being separated from the wheat and 10 other material before the grain, deposited upon the belt, is distributed over the portion of the belt covered with the larger indentations 21.

As the machine continues to operate, the 15 grain will be gradually distributed over the face of the belt by the action of the revolving feed screw 64, and as the kernels of wheat drop into the larger pockets 21 of the belt, they will in like manner be elevated 20 to the rear of the machine and be delivered into the conveyor trough 65. As the grain is being thus conveyed across the indented surface of the inclined belt all of the wheat will be separated from the oats and coarser 25 materials by means of the pockets 21 being of such size as to pick up only the wheat. The wheat, being considerably heavier than the oats and coarser materials, also has a tendency to settle to the bottom, thereby 30 causing the oats, etc., to float on top of the mass where it will be in direct contact with the inclined feed screw 64. Owing to the tail end of the screw 64 being higher than the receiving end thereof, it will have a 35 sweeping effect upon the coarser material floating on top of the mass, resulting in it being swept or conveyed to the tail end of the machine, and discharged into a separate spout 77, secured to the end thereof.

40 From the foregoing, therefore, it will be readily seen that as a result of the rolling and tumbling actions of the mass of grain carried on the belt, every particle of the mass will at some time or other be brought 45 into direct contact with the indented surface of the belt resulting in all the small seeds and wheat being elevated to the rear of the machine by means of the pockets 20 and 21, while the oats and coarser material is dis- 50 charged from the end of the machine into the receiving spout 77. Thus, a thorough and complete separation will be made of the different materials.

55 As shown in Figures 7, 8 and 9, the opposed side edges of each belt section 19 is preferably provided with loops 79, arranged in staggered relation and adapted to interlock with similar loops on adjacent sections, as particularly shown in Figure 3. A rod 60 78 is passed through the thus aligned loops for the purpose of pivotally connecting together the belt sections to form an endless belt or apron.

65 In Figure 10, there is shown a modified belt construction wherein the shape of the

indentations or pockets provided in the belt's surface has been slightly modified. There is also shown a modified form of hinge or connecting means for pivotally connecting together the adjacent belt sections 19. As 70 here shown, the forward or leading edge of each section is preferably formed so as to provide an irregularly shaped loop consisting of a downwardly extending wall 81, bottom wall 82 and an upwardly and inwardly projecting inclined wall 83, so arranged as to provide a longitudinal gap 84 extending the entire length of the belt section. The rear or following edge of each section 19 is preferably bent downwardly and inwardly to 80 form a hook 85, the end of which is adapted to be fitted into the longitudinal gap 84 provided in the forward edge of the following adjacent section. When the belt sections are thus connected or joined together, the bottom of the hook 85 will be in direct engagement with the upper edge of the inclined wall 83, which will function as the pivot point between the two sections. It will also be noted that when the belt sections are thus 85 joined together, the pivot point therebetween will be in alignment, substantially, with the outer indented surfaces of the belt sections, thereby providing a joint or hinge which will not open or gap when passing over the 90 peripheries of the pulleys or sprockets, thus preventing any materials or small seeds from getting thereinto. In the drawings, I have shown the loop formed in the leading edge 95 of each section and the hook 85 in the rear or lagging edge thereof. It is to be understood, however, that the sections may be reversed if desired, so that the hooks 85 will be on the leading edge of each section, as 100 they will function equally well in either direction of movement.

In Figure 10^A, there is shown another form of belt construction wherein a circular loop 86 is formed on one edge of each belt section, which similarly extends from end to end of the section. A longitudinal gap 87 is similarly provided to receive the hook 85 in a manner similar to that shown and described with reference to Figure 10.

110 In Figures 12 and 13, there is shown a modified form of separator employing an inclined shelf 82 to prevent the grain from sliding off the belt, in place of the curved plate 59, shown in Figures 2 and 5. This shelf extends from end to end of the machine and preferably has its receiving or head end slightly higher than the opposite or discharge end thereof. A brush 83 is secured to the lower edge thereof adapted to contact with the surface of the belt to close the gap between the shelf and the belt.

115 Thus when the grain is fed through the feed roll 49, from the hopper 39, it will drop into the V-shaped trough formed by the inclined surface of the belt and the shelf 82. 120 125

As the belt travels, it will impart to the material deposited thereon, a rolling action, as hereinbefore described with reference to Figures 2 and 5. Such rolling action will cause the material to gradually work its way across the width of the apron, caused by the discharge end of the shelf 82 being lower than the receiving end thereof. As the grain and other material thus travel across the indented surface of the belt, all small seeds and particles will first be separated therefrom by means of the small indentations or pockets 20. As the larger material continues to travel across the face of the belt it will be brought into contact with the larger pockets 21 which will pick out all the wheat. In Figures 11 and 12 the belt is shown as having three different sizes of pockets, the largest pockets 23, being adapted to pick out such material as durum wheat which is too large to be elevated by the pockets 22. The coarser material such as wild oats, barley, sticks, etc., will be discharged out through the end of the machine into the spout 77. In Figure 12, the rotary brush 73 has also been eliminated as it may be found practical to operate the machine without it.

While I have described the machine particularly for separating wheat from seeds and coarser material, it will be understood that I do not limit myself to separation of any particular grain, as the machine may be used for separating other grains such as barley, rye, rice, legumes etc.

Furthermore, I have disclosed in the foregoing specification and the drawings the preferred form of my invention but I do not limit myself to the details of construction shown and described except as the same come within the scope of the following claims.

I claim as my invention:

1. A separator comprising a frame, a flexible belt movably mounted at an angle on said frame, the outer exposed surface of said belt having indentations formed therein, adjustable means adapted to regulate and control the flow of material discharged onto the indented surface of said belt, and means for holding all except the coarser material in said separator until a complete separation thereof has been obtained and means for collecting the coarser material at the top of the mass and discharging it laterally from said frame.

2. A separator comprising a frame, an inclined belt supported upon said frame, the outer exposed surface of said belt having longitudinally extending groups of different sized indentations progressively arranged across the face thereof, with the smaller indentations adjacent the receiving side of the belt, a hopper, an adjustably mounted slide, a feed roll, and means for horizontally distributing the material across the indented

surface of said belt, and means for discharging the coarse material and holding the finer material in said separator until a complete separation thereof has been obtained.

3. A separator comprising a frame, an inclined belt having an indented surface, and feed means mounted within said frame, and extending transversely thereof.

4. A grain separator comprising a casing, a belt having an indented surface arranged at an angle therein, a feed screw arranged at an angle within said casing, and means adapted to prevent the grain and other materials from falling off the lower inclined surface of said belt.

5. A separator comprising in combination a casing, a flexible belt arranged at an angle and supported by said casing, a material delivering means, a feed screw adapted to feed the material across the indented surface of said belt and to discharge the coarser material from said casing.

6. A machine of the class described comprising a suitable frame, a separator mounted therein and having an inclined separating surface provided with indentations or pockets, and means operating through the upper portion of the mass of material for feeding and delivering the coarser refuse material at one side of said separator while the finer material is collected in said pockets.

7. A machine of the class described comprising a frame, a separator mounted therein and having an inclined surface provided with indentations or pockets, means for delivering the material to be separated upon said separator, the seeds and finer material working to the bottom of the mass and being collected in said pockets, and means on the discharge side of said separator for receiving the material so separated and discharging the finer material on one side of said separator and the coarser material on the other side.

8. A separator comprising a casing having a discharge opening at one side thereof, traveling conveying means for supporting and agitating the material to cause the finer material to gravitate to the bottom of the pile, and means for holding the material on said supporting means and directing it transversely towards said discharge opening.

9. A separator comprising a casing having a discharge opening, means having a separating surface for receiving the material and agitating the same to cause the finer material to gravitate to the bottom of the pile, and means operative in the pile at an angle to said separating surface to remove the coarser material and deliver it to said discharge opening.

10. A separator comprising a casing for material to be separated, means for supporting the material and agitating the same

to cause the finer material to gravitate to the bottom of the pile, and means operating through the top of the pile for removing the coarser material.

5 11. A method of separating comparatively light and coarse material from finer and heavier material which consists in delivering the mixture to the pocketed surface of a separator, agitating the same to cause the 10 lighter and coarser material to seek the top of the pile while the finer and heavier material works to the bottom and is collected in the pockets of the separator, and then sweeping through the top of the pile transversely of the separator to collect and discharge the lighter and coarser material.

12. A separator comprising a frame, and an inclined flexible belt supported by said frame, the outer exposed surface of said 20 belt being provided with indentations, means for feeding the material onto the inclined surface of said belt and distributing it across the indentations, said frame having a discharge, means for holding all except the 25 coarser material in said separator until a complete separation thereof has been obtained, and means for collecting the coarser material at the top of the mass to be separated and delivering it to said discharge.

30 13. The combination with a frame, of an inclined separator mounted therein and having indentations or pockets in its surface, means for delivering the material to the indentations, said separator having a lateral 35 discharge, and means for holding the material to be separated on said separator and directing it transversely thereof across the indentations toward said discharge, said opening receiving the coarse material while 40 the fine material is collected by the indentations of said separator.

14. A machine of the class described comprising a suitable frame, a separator mounted therein and having an inclined surface 45 provided with pockets, means for delivering the material to be separated to said pockets to separate the fine material, said separator having a discharge at one side for the coarse material, means mounted transversely of said separator to direct the mass 50 of material across said separator, the fine material being collected by the pockets of said separator during such passage and the coarse material flowing through said discharge.

55 15. A machine of the class described comprising a frame, a separator mounted therein and having an inclined surface provided with indentations or pockets, said frame 60 having a discharge opening at one side adapted to receive the coarser material and having means for preventing the entrance to said discharge of the finer material, means for delivering the material to be separated to the pockets, the finer material settling to

the bottom of the mass as it is moved along and entering the pockets, the coarser material working to the top, and means operating through the upper portion of the material for feeding and delivering the coarser material to said discharge, the finer material being held back by said preventing means. 70

16. A machine of the class described comprising a frame, a separator mounted therein and having an inclined surface provided with 75 indentations or pockets, said separator having a discharge at one side to receive the coarse and refuse material, means for delivering the material to the indentations and means directing it across said separator, and 80 a rotating means operating through the mass of material for feeding and delivering the coarse and refuse material to said discharge.

17. A machine of the class described comprising a frame, a separator mounted therein 85 and having an inclined surface provided with indentations or pockets, said separator having a discharge at one side to receive the coarse and refuse material, means for delivering the material to the indentations, and a 90 rotating means operating through the mass of material for feeding and delivering the coarse and refuse material to said discharge, said rotating means gradually diverging from the surface of said separator. 95

18. A separator comprising a casing having a feed at one side of the casing and a discharge at the other side, means for supporting the grain and agitating the same to cause the finer material to gravitate to the bottom of the pile of grain, and means operative in the upper layer of the pile of grain to remove the coarser material from the feed to the discharge and discharge the same. 100

19. A separator comprising a casing having a feed at one side to deliver the material and an opening at the other side to discharge the same, constantly moving means at the feeding point to agitate the material and to remove portions from the bottom of the pile, and means operative in the pile to spread the same over the removing means and to discharge the coarser material that has risen to the top of the pile through the casing discharge opening. 110

20. A separator comprising a casing having a material receiving entrance and a discharge, moving means having pockets to agitate and separate the material into coarser and finer portions and means for directing the material across the pockets of said moving means, said directing means being positioned to sweep the top of the pile of material and direct the coarse and refuse material toward and through said discharge. 120

21. A separator comprising a casing having openings to receive the material and discharge the same, means moving at an incline to agitate the material and having pockets or indentations to remove portions of mate- 130

rial from the bottom of the pile, means operative in the upper layer of the pile of material to spread the same over said inclined means and discharge the coarser material that has risen to the top of the pile through said discharge opening, and means operating to dislodge from said pockets the coarser particles which may have fallen therein to return the same to said pile.

- 10 22. A separator comprising a casing having openings to receive the material and to discharge the same, and means moving at an incline to receive the material and agitate it and having pockets or indentations to remove portions of material from the bottom of the pile, means operative to distribute the material over said inclined means and dis-

charge the coarser material through said discharge opening, and means for brushing from said pockets any coarse material that 20 may have lodged therein and returning it to said pile.

23. A separator comprising a casing having a discharge opening, a traveling belt having a separating surface for receiving 25 and agitating the material to cause the finer material to gravitate to the bottom of the pile, and inclined means for directing the material across said supporting surface and delivering the coarser material to said discharge opening.

In witness whereof, I have hereunto set my hand this 10th day of November, 1923.

JOHN A. PERKINS.
